[57] **CLAIM**

The ornamental design for a combined table and side extension unit, substantially as shown and described.

DESCRIPTION

FIG. 1 is a perspective view of a combined table and side extension unit, which shows my new design;

FIG. 2 is a top plan view thereof;

FIG. 3 is a front elevational view, the rear view being

substantially a mirror image thereof;

FIG. 4 is a side elevational view as viewed from the

right of FIG. 3; and

FIG. 5 is a side elevational view as viewed from the left of FIG. 3.

FIG. 1

FIG. 2

FIG. 3

FIG. 4

FIG. 5
